UNITED STATES PATENT OFFICE.

IDA SCHIKORRA, OF PHILADELPHIA, PENNSYLVANIA.

DOUCHE OR BED PAN.

No. 924,383.

Specification of Letters Patent. Patented June 8, 1908.

Application filed June 8, 1908. Serial No. 437,295.

To all whom it may concern:

Be it known that I, IDA SCHIKORRA, a citizen of the United States, residing in Philadelphia, Pennsylvania, have invented certain

5 Improvements in Douche or Bed Pans, of which the following is a specification.

The main object of my invention is to construct a douche or bed pan in such a manner as to prevent the pan slipping from under

10 the patient when in use.

A further object of the invention is to so design the pan that the patient can rest with ease upon it in the proper position and all the douche water will flow into the pan and 15 room will be provided for a quantity of water.

In the accompanying drawing:—Figure 1, is a perspective view of my improved douche or bed pan; Fig. 2, is a longitudinal sectional view on the line 2—2, Fig. 3; Fig. 3, is a 20 sectional view on the line 3—3, Fig. 2.

The douche pan has a bottom plate A, shaped as clearly shown in Fig. 2, having a circular convex projection a at one end and 25 a deep depression a' extending from one side of the pan to the other and terminating at the rear end in a comparatively sharp rib a'' where it joins the end b. The side walls b' of the pan are slightly tapered as shown and 30 the upper edges of the sides and ends have a rolled rim b'' so as to provide a smooth surface for the patient. Extending from one side member b' to the other is a seat section c on which rest the buttocks of the person

35 using the pan. It is shaped to conform to that portion of the body and to relieve the spine and there is a lip formed at the edge c' and the center portion of this edge is depressed as at c'' so as to give additional room 40 at this point to allow water to more readily flow from the patient into the pan. The convex projection a of the bottom A forms a cavity on the inner side of the pan directly under the lip and gives sufficient room for 45 the flow of water, and access can be readily had to that portion of the pan under the seat section c.

It will be noticed that when the pan is in use the body of the user rests comfortably 50 upon the section c; the section being tapered to almost a point at c''. This causes the projecting portion a of the bottom A to force itself into the bed and the tendency to move back from the patient is checked by the 55 abrupt edge a'', which is also forced into the bed by the weight of the user and the mate-

rial of the bed works up into the cavity a' and the pan is thus held firmly on the bed.

In using my improved pan the body of the patient rests over about one-half of the 60 pan and the pan is of such width as to be about equal to the width of the patient, thus making the pan comfortable and avoiding the concentration of the pressure on the 65 spine, at the same time holding the pan from tipping at the outer end.

One of the great disadvantages in using the average pan is the liability of the pan to slip from under the patient and this is entirely obviated by the construction above 70 described.

The edges at the junction of the sides b' and the bottom A are comparatively sharp 75 so as to prevent any lateral movement of the pan.

Numerous tests have been made with this pan and when once located on the bed it is firmly held in position under the patient, and the patient can move without the liability of the pan slipping out of position.

The pan can be readily cleansed when desired as the cavity a under the lipped portion is sufficient to allow the hand to be passed underneath the seat section c, so that all portions are accessible for cleansing.

While in the drawings I have shown the pan made of sheet metal it will be understood that it may be made of porcelain or other material without departing from the essential features of the invention.

I claim:—

1. A douche or bed pan, having a bottom with an upwardly extending and relatively deep cavity therein, there being a sharp edge at one end of the pan whereby it is enabled to embed itself in the bed, said bottom having also a downwardly extending projecting portion coöperating with said edge to prevent movement of the pan when pressure is applied.

2. A douche or bed pan having a bottom section, side sections, and an inclined seat section extending partly over the bottom of the pan, an outwardly extending projection in the bottom of the pan forming a cavity directly under the inner edge of the seat section, said bottom having a transverse cavity extending from one side of the pan to the other and terminating in a comparatively sharp edge where it joins the rear of the pan, so that the pan will embed itself in the bed.

3. A douche or bed pan having a bottom,

side and end walls, and an inclined seat section shaped to fit the contour of the body and so arranged that the weight of the body will rest directly on the pan, the underside of the pan having a projection and a relatively deep, inwardly extending recess so formed that the pan will be embedded in the bed and will not slip from under the patient.

In testimony whereof, I have signed my name to this specification, in the presence of 16 two subscribing witnesses.

IDA SCHIKORRA.
